ROBERT S. BOLGER, OF RICHMOND HILL, NEW YORK.

ART OF SPOOL MANUFACTURE.

1,366,336.

Specification of Letters Patent. Patented Jan. 18, 1921.

Application filed April 3, 1919. Serial No. 287,123.

To all whom it may concern:

Be it known that I, ROBERT S. BOLGER, a citizen of the United States, residing at Richmond Hill, in the county of Queens 5 and State of New York, have invented new and useful Improvements in Art of Spool Manufacture, of which the following is a specification.

This invention relates to improvements in 10 the art of spool manufacture, pertaining more particularly to spools and analogous articles formed of paper stock.

While spools and analogous articles—such for instance as cops, etc.,—have heretofore been produced from paper stock material, the production has generally been of a type involving various difficulties—either in production or in the resulting product—tending to increase the factor of cost of 20 production or an inferior product.

For instance, it is the practice to produce such structures by winding a blank upon itself to provide a plurality of convolutions adhesively connected, and then add a second blank or blanks to provide the end configuration of the cop or spool the latter blank or blanks being wound upon the previously wound blank so as to produce the proper end configuration by a plurality of superposed convolutions. This not only requires the use of two or more independent blanks, but also requires at least two independent and successive operations to provide the wound condition, after the blanks have been 30 produced, since winding of the first blank to its substantially completed form is required before the winding of the end configuration blank or blanks can be started. The requirements for the production and 40 handling of the two or more types of blanks and the necessity for handling these blanks as separate elements and under successive operation conditions provides a material factor in the cost of production of the article.

In addition, the blanks themselves carry certain characteristics which affect the cost of production, either with respect to waste of material in cutting the blanks or in the 50 requirement for collecting differently positioned blanks to permit their use as a source of supply for the individual blanks actually used. This is especially true with respect to the blanks used in producing the 55 end configurations of the spool or cop in which the convolutions are of different

widths to provide the desired contour of such end configurations, thus practically requiring a blank varying in width from one end to the other, producing a condition inherently tending to increase the cost. 60

The present invention is designed to overcome these difficulties in a manner to greatly decrease the cost of manufacture. This is had primarily by the use of a single blank 65 in the production of the spool or cop, with the blank of such form that it can be produced from a strip of paper stock by a simple cutting operation, the form of the blank being such that wastage of material is reduced to a minimum and is provided at such 70 point as to not affect the cutting operation or the product.

The width of the strip corresponds to the length of the spool or cop or the latter may 75 be produced by dividing the spool length, in which case the strip would have a width double that of the cop length,—and one of the fundamentals of the present invention is the fact that the blank has varying cross 80 sectional configurations at spaced apart points in its length with a portion of the blank of constant characteristics extending throughout the width of the strip, this portion being of such an area and so located 85 that it forms more than a single convolution of the spool or cop and is preferably, although not absolutely essentially positioned in the completed spool as an intermediate portion or zone of the spool convolutions. In other words, the inner and 90 outer convolutions of the completed spool are varied in these cross sectional configurations, but an intermediate portion—which controls the length of the spool and can be considered as forming the foundation—is located at an intermediate point; the particular arrangement may be considered as producing both inner and outer convolutions with respect to this foundation zone. 95

Another feature lies in the fact that the spool may, if desired, be produced without the adhesive connection of successive convolutions. Adhesive may be limited to outer convolutions, or a separate strip may be 105 secured about the wound end configurations and adhesively secured thereto or not, or the wound condition may be maintained by the use of a band or an end cap—metallic or otherwise—this being made possible by 110 the fact that the convolutions are formed from an integral blank.

By this arrangement it is possible to produce the blanks successively from a strip or web without material loss or wastage, the portion providing the inner convolutions of 5 one spool being obtained from the portion of the strip which provides the convolutions of the end configurations of another spool. This not only permits of the cutting of the blank in simple manner, as by the use of 10 complementary rotating cutting dies, but in addition, provides a form of blank which can be readily provided with the adhesive material by the use of simple mechanism with the adhesive in the form of a solid 15 coating or in the form of zones, since the entire structure is made from a simple and single blank.

To these and other ends, therefore, the nature of which will be readily understood 20 as the invention is hereinafter disclosed, said invention consists in the improved methods and the products resulting therefrom, as hereinafter fully described, illustrated in the accompanying drawings, and more particularly pointed out in the appended claims.

In the accompanying drawings, in which similar reference characters indicate similar parts in each of the views,

Figure 1 is a plan view of a strip divided 30 into blanks for practising the invention.

Fig. 2 is a plan view of a single blank, said figures showing the blanks considerably shorter in proportion to their width than blanks used in actual practice, the actual 35 length of said blanks being approximately $2\frac{1}{2}$ times that shown in said figures relative to the width of the blanks therein.

Fig. 3 is a face view of a completed spool, a portion being broken away.

Fig. 4 is a section taken on line 4—4, of 40 Fig. 3.

Fig. 5 is a detail sectional view showing the use of a retaining band.

Fig. 6 is a detail sectional view showing 45 the use of a cap.

The blank employed, indicated at 10, embodies a zone *a* of the full width of the blank and positioned intermediate the ends of the latter, a zone *b* which projects in one direction from zone *a* and which has its side edges spaced from the plane of the side edges of zone *a*, these side edges being preferably inclined to such planes so as to produce a more or less tapered appearance to 55 this zone—the arrangement having somewhat the appearance of a tongue; the remainder of the blank is in the form of a pair of projecting portions *c* extending from zone *a* in a direction opposite to that of zone *b*, and which may be considered as a third zone, 60 these portions *c* having their outer side edges on the planes of the side edges of zone *a*, with the inner edges of these portions inclined to such planes, thus providing a 65 space—flared outwardly from zone *a*—be-

tween portions *c*. The blank so described is one which is designed for the production of a spool and hence is formed with two portions *c*, the width of zone *a* corresponding to the length of the spool; where the structure is employed as a cop, the width of zone *a* would obviously be increased, and one of the portions *c* would be omitted.

The several zones are defined from each other by cut or cutting lines extending angularly to the planes of the strip side edges,—preferably extending in directions substantially transverse to such planes.

As shown, zones *b* and *c* are more or less complementary to each other. In fact, zone *b* of one blank is produced by utilizing the stock—or a part of the stock—taken from zone *c* of another blank in producing the spaced portions of that zone, as shown in Fig. 1, this figure showing a strip *s* which may be a portion of a web of uniform width and from which the blanks are successively formed as by the use of a rotating cutting apparatus which carries cutting dies suitable for cutting the web at the proper points.

As shown in Fig. 1, the actual length of zone *b* is less than the length of portions *c*, a distance—*x*—representing a portion of the stock which may be wasted. This distance may be varied to meet the particular form 95 of spool which is to be manufactured, and such distance may extend substantially the full length of portions *c* so that the side edges of the blank would all be in the same plane, practically combining zones *a* and *b* 100 into one zone. However, it is preferred to employ zone *b*, in the form shown and the particular length of this zone which is to be employed may be varied in meeting the exigencies of use through varying the distance *x*.

In forming the spool, zone *b* is first wound—thus producing the inner convolutions of the spool—zone *a* being wound upon zone *b*, the continued winding then winding 110 portions *c* upon zone *a*. This has the effect of producing a spool formation in which the inner convolutions of the spool are of less width than those of the intermediate convolutions—the latter being the full length 115 of the spool—the difference in width, however, being comparatively small, since the portions omitted at the sides of zone *b* are provided by the narrower parts of portions *c*; hence the reduction will not materially 120 affect the ability to use the spool on a spindle, especially where the spool carries the closure usually applied at the ends of spools—the punctured paper tending to enter into this space and thus aid in preventing 125 damage to the interior of the spool.

While this zone *b* of reduced width does not materially affect the operation of the spool in use, it is of material advantage in the cost of production of the spool, for the 130

reason that it forms a portion of the material from which the body portion of the spool is produced. This body portion is required to have a certain number of convolutions in order to provide the desired diameter and strength, and zone *b* provides a portion of the supply for these convolutions; if the form of zone *b* is changed to substantially increase the length of zone *a* 5 in order to provide the requisite number of convolutions, the change in result will be that a less number of blanks could be obtained from a given length of strip. For instance, if the distance between the end *b'* 10 of zone *b* to the opposite end of zone *a* represents the length of material required to produce the desired number of convolutions, it will be readily understood that the extreme end of zone *c* of an adjacent blank will begin 15 at the line *b'* instead of at the end of zone *a* as in the preferred form, so that instead of the distance between points *m* and *n* in Fig. 1 being the measure to indicate the number of blanks which may be obtained from a 20 strip, such measure would be provided by the distance between points *b'* and *n*, in which case not only would a lesser number of blanks be produced from a strip, but wastage would be increased through the loss 25 of all of the material between portions *c*.

As will be understood, this saving provides a material factor in the cost of production of spools in quantity, representing approximately 25% of the cost of material, 30 through the possibility of increasing the number of blanks to be secured from a given length from three to four.

After zone *a* has been wound upon zone *b*, the continued winding places portions *c* as 35 added convolutions at the ends of the spools, the added convolutions providing a tapered effect as the convolutions are added, the outer edges of portions *c*, however, extending on the same plane as these edges of zone *a* 40 so that the actual end faces of the spool are on a single plane.

While not essential, as presently pointed out, it is preferred that the convolutions be adhesively connected, this result being provided by applying adhesive material to a 45 face of the blank, either with a solid coating or with a zonal or spotted effect as may be desired, it being preferred to omit adhesive at the end *b'* of zone *b* a distance sufficient 50 to leave the exposed face of the inner convolution free from adhesive.

The presence of this adhesive especially where the blank is tightly rolled—an operation made possible by the formation of the 55 particular blank shown—there may be caused a tendency of adhesive to ooze out at the edges as the winding continues. This is not 60 of material disadvantage in connection with the side edges of zone *b* and inner edges of 65 portions *c*, since this exposed adhesive, if

permitted to dry before treatment, may act as more or less of a filler on the inner face of the spool and portions and of the cavity on the interior of the spool, thereby permitting the use of a tool to smooth these 70 portions and produce a closer approach to a uniform surface at these points, and at the same time the presence of this adhesive filling would tend to more firmly unite the convolutions through the more or less connecting action at the edges of the convolutions. 75

As will be readily understood, the winding is substantially continuous in one direction throughout the formation of the spool, so that there is no handling of a plurality 80 of blanks in the formation of the spool, and there is no requirement of adjusting one blank relative to another in order that the completed product will have the outer end faces of the spool extending on a single 85 plane, it being readily understood that more or less care is required in connecting a separate blank for the end convolutions owing to the difficulty of producing an accurate registration and alinement of the outer edge 90 of such added blank with the outer edge of the blank of the body portion. This difficulty will be readily understood in considering the fact that the relative positions of the convolutions in a closely wrapped winding is practically determined by the initial convolution, any error in position of that convolution being accentuated as the other convolutions are added. Since, in the present invention, portions *c* are integral parts 95 of the blank, there is no adjustment required and assurance is had that the convolutions produced by winding of these portions upon the convolutions of zone *a* will provide the desired uniformity in the planes 100 of the end faces. As a result, the cost of manufacture of the spools are thus further materially reduced through the elimination of the necessity of providing such accurate 105 adjustment. 110

Obviously, this saving, in addition to the savings provided by the entire elimination of the necessity for operating with different types of blanks on the same spool and the proper assembly of the different blanks, etc., 115 act as factors in producing a decrease in cost of production of the spool.

As heretofore pointed out, the spool preferably has its convolutions adhesively connected. This, however, is not essential, since 120 the adhesive may be limited to the outer convolutions, or, if desired, a separate paper strip may be wrapped about and adhesively connected to the outer convolutions, or the adhesive connection may be omitted and the 125 wound condition maintained by a simple band of suitable material or by a cap placed over the end.

For instance, in Fig. 5, I show the use of a band-like element 130 which may be a paper

strip with overlapping secured ends or it may be a solid metallic band or a resilient split band the purpose being to retain the spool in its wound condition by preventing 5 unwinding of the outer convolutions; it may be desirable in such case to adhesively connect a few of the inner convolutions.

In Fig. 6, I have shown this same result obtained by the application of a cap 16 of 10 suitable material, thus preventing the unwinding action by preventing expansion of the diameter of the wound convolutions.

No specific form of mechanism is disclosed for cutting the strip into the blanks, nor for 15 adhesively coating and winding the blanks. These operations can obviously be performed by hand, as for instance by the use of a templet for giving the desired shape to the blank in cutting and the use of a suitable 20 tool as a mandrel for winding. It will be understood, of course, that for commercial purposes, the cutting and winding will be by the use of proper mechanisms, the particular construction of which may be varied to meet 25 the particular conditions, the present disclosure not being dependent upon any specific type of mechanism to permit this practice.

As heretofore pointed out, the arrangement 30 is capable of use in the formation of cops, etc. These may be provided by forming a spool structure of a length twice that of the cop length, the spool then being divided midway of its length, thus producing 35 two cops. In such case the width of the strip and of zone *a* will be twice that of the length of the cop. Or the cops may be made individually by making the width of zone *a* equal to the length of the cop, one of the 40 portions *c* being omitted, since the enlargement is carried by one end only of the cop, and in such case zone *b* may have the edge on one side extend to the plane of the corresponding edge of zone *a*, this edge being 45 that corresponding to the side of the strip on which portion *c* is omitted, the opposite side edge being as shown.

It is to be understood, of course, that in referring herein to "spool" the term is not 50 intended to be limited to a structure having the enlargements at opposite ends excepting where the particular wording employed specifically limits the term to this specific meaning; in its broader aspect, the term would 55 of course, include more or less analogous structures, such for instance as cops, etc., in which the enlargement at one end is omitted.

While I have herein shown and described 60 various ways for practising the present invention, it will be readily understood that changes and modifications therein may be found desirable or necessary in meeting the various exigencies of use, and I desire to be understood as reserving the right to make 65 any and all such changes or modifications

in so far as the same may fall within the spirit and scope of the invention as expressed in the accompanying claims when broadly construed.

Having thus described my invention, what 70 I claim as new is:—

1. In the art of spool manufacture, the method of producing a spool formation from paper stock and which consists in winding upon itself a blank of varying cross-sectional characteristics at spaced-apart points in its length to form a plurality of integrally-connected convolutions in which a blank portion of constant characteristics forms more than a single convolution of the spool and provides the exposed supporting face of substantial length throughout for the contents to be carried by the spool, and securing the convolutions in wound relation. 75

2. In the art of spool manufacture, the method of producing a spool formation from paper stock and which consists in winding upon itself a blank of varying cross-sectional characteristics at spaced-apart points in its length to form a plurality of integrally-connected convolutions in which a blank portion of constant characteristics forms more than a single convolution of the spool and is located intermediate the inner and outer convolutions, and which provides the exposed supporting face for the contents to be carried by the spool, and securing the convolutions in wound relation. 90

3. In the art of spool manufacture, the method of producing a spool formation from paper stock and which consists in winding upon itself an adhesively-surfaced blank of varying cross-sectional characteristics at spaced-apart points in its length to form a plurality of integrally-connected convolutions in which a blank portion of constant characteristics forms a zone composed of more than a single convolution and positioned intermediate the inner and outer convolutions and provides the exposed supporting face for the contents to be carried by the spool. 100

4. In the art of spool manufacture, the method of producing a spool formation from paper stock and which consists in winding upon itself an adhesively-surfaced blank of varying cross-sectional characteristics at spaced-apart points in its length to form a plurality of integrally-connected convolutions in which a blank portion of constant characteristics forms more than a single convolution of the spool and provides the exposed supporting face for the contents to be carried by the spool, other convolutions each of less width than said portion being superposed thereon to provide a confining end configuration for such contents. 115

5. In the art of making spools from paper stock and wherein the blank is wound into spool formation to form the supporting sur- 120

- face for the contents carried by the spool and a confining end for such contents, the step which consists in the production of a succession of such blanks from a strip having a width equal to the length of the completed spool and which consists in producing a zone of the blank with constant cross-sectional characteristics and having the full width of the strip, and a second zone of less width throughout the length of the zone than such zone of constant characteristics, said zones being defined from each other by a cutting line extending substantially transverse to the strip length. 10
6. In the art of making spools from paper stock and wherein the blank is wound into spool formation to form the supporting surface for the contents carried by the spool and a confining end for such contents, the step which consists in the production of a succession of such blanks from a strip having a width equal to the length of the completed spool and which consists in severing the blank to form a zone of the blank with constant cross-sectional characteristics and having the full width of the strip, and a second zone of less width throughout the length of the zone than such zone of constant characteristics, said zones being defined from each other by a cutting line extending substantially transverse to the strip length, said second zone having its cross-sectional characteristics varied at spaced-apart points of the zone. 15
7. In the art of making spools from paper stock and wherein the blank is wound into spool formation to form the supporting surface for the contents carried by the spool and a confining end for such contents, the step which consists in the production of a succession of such blanks from a strip having a width equal to the length of the completed spool and which consists in severing the blank to form a zone of the blank with constant cross-sectional characteristics and having the full width of the strip, and a zone at each end of said zone of constant characteristics, the material in said end zones being each of less width throughout the length of the zone than such zone of constant characteristics, said zones being defined from each other by cutting lines extending substantially transverse to the strip length. 20
8. In the art of making spools from paper stock and wherein the blank is wound into spool formation to form the supporting surface for the contents carried by the spool and a confining end for such contents, the step which consists in the production of a succession of such blanks from a strip having a width equal to the length of the completed spool and which consists in severing the blank to form a zone of the blank with constant cross-sectional characteristics and having a full width of the strip, and a zone at each end of said zone of constant characteristics, said zones being defined from each other by cutting lines extending substantially transverse to the strip length. 25
9. In the art of making spools from paper stock and wherein the blank is wound into spool formation to form the supporting surface for the contents carried by the spool and a confining end for such contents, the step which consists in the production of a succession of such blanks from a strip having a width equal to the length of the completed spool and which consists in severing the blank to form a succession of zones of constant cross-sectional characteristics and of full width of the strip at spaced-apart points in the length of the strip and with each zone forming a part of an individual blank, and severing the blank to form from the intermediate strip portions a zone at each end of and with the material in each of less width than such zones of constant characteristics, one end zone of a blank and the other end zone of the adjacent blank being formed from the same intermediate portion, the respective zones being defined from each other by cutting lines extending substantially transverse to the strip length, one of said end zones having a length equal to the length of such intermediate strip portion and embodying two zonal portions spaced apart a distance equal to the width of the other end zones on a cross section of such intermediate portion of the strip. 30
10. In the art of manufacturing spools from blanks of sheet material rolled to form a hollow laminated spool having a central barrel of substantial length throughout, a blank adapted to form a spool having concave ends, said blank being composed of a barrel-forming zone at least equal in length to said barrel portion, and an end zone tapering inwardly from the outer edges of said barrel-forming zone. 35
11. In the art of manufacturing spools from blanks of sheet material rolled to form a hollow laminated spool having a central barrel of substantial length throughout, a blank adapted to form a spool with outwardly projecting flanges at the ends thereof, said blank including a barrel-forming zone having a width equal to the length of the spool and flange forming tongues extending lengthwise of the blank in continuation of the outer edges of said barrel-forming zone, the inner ends of said extensions being substantially spaced from each other. 40
12. In the art of manufacturing spools from blanks of sheet material rolled to form

a hollow laminated spool having a central barrel of substantial length throughout, a blank adapted to form a spool, said spool being provided with end flanges and concave ends, a blank including a central barrel-forming zone having a width at least equal to the length of said barrel, an extension at one end of said zone tapering inwardly therefrom, and flange-forming extensions at 10 the other end of said zone forming continuations of the opposite edges of said zone and having their inner ends substantially spaced from each other.

13. A blank of paper stock adapted to produce spools when wound into convolution form, said blank having a plurality of integrally-connected zones, one of said zones having a uniform width equal to the length of the spool and having a length to produce 15 more than a single convolution of the blank, a second zone being of less width than said first mentioned zone, said zones being defined by a contour formation extending substantially transverse to the direction of 20 length of the blank.

14. A blank of paper stock adapted to produce spools when wound into convolution form, said blank having a plurality of integrally-connected zones, one of said 30 zones having a uniform width equal to the length of the spool and having a length to produce more than a single convolution of the blank, a second zone the material in which is of less width than said first mentioned zone, said zones being defined by a contour formation extending substantially transverse to the direction of length of the blank, said second zone having a side edge extending in the plane of a side edge of the 35 first mentioned zone with the opposite side edge arranged to produce a tapered formation to the zonal portion.

15. A blank of paper stock adapted to produce spools when wound into convolution 45 form, said blank having a plurality of integrally-connected zones, one of said zones having a uniform width equal to the length of the spool and having a length to produce more than a single convolution of the blank, a second zone the material in which is of less width than said first mentioned zone, said zones being defined by a contour formation extending substantially transverse to the direction of length of the blank, said 50 second zone embodying two portions spaced apart with a side edge of each portion extending in the plane of a side edge of the first zone.

16. A blank of paper stock adapted to 60 produce spools when wound into convolution form, said blank having a plurality of integrally-connected zones, one of said zones having a uniform width equal to the length of the spool and having a length to produce 65 more than a single convolution of the blank

and zones at the opposite ends of and the material in which is of a less width than said first mentioned zone, said zones being defined by contour formations extending substantially transverse to the direction of 70 length of the blank.

17. A blank of paper stock adapted to produce spools when wound into convolution form, said blank having a plurality of integrally-connected zones, one of said zones 75 having a uniform width equal to the length of the spool and having a length to produce more than a single convolution of the blank and zones at the opposite ends of and the material in which is of a less width than 80 said first mentioned zone, said zones being defined by contour formations extending substantially transverse to the direction of length of the blank the respective widths of said end zones on a cross section of one of 85 the zones being such as to produce a total width equal to the width of the first zone.

18. A blank of paper stock adapted to produce spools when wound into convolution form, said blank having a plurality of integrally-connected zones, one of said zones having a uniform width equal to the length of the spool and having a length to produce more than a single convolution of the blank and zones at the opposite ends of and the 95 material in which is of a less width than said first mentioned zone, said zones being defined by contour formations extending substantially transverse to the direction of length of the blank, each of said end zones 100 having side edges inclined to the plane of a side edge of the first zone.

19. A blank of paper stock adapted to produce spools when wound into convolution form, said blank having a plurality of integrally-connected zones, one of said zones having a uniform width equal to the length of the spool and having a length to produce more than a single convolution of the blank and zones at the opposite ends of and the 110 material in which is of a less width than the first mentioned zone, one of said end zones embodying a pair of zonal portions spaced apart and each having a side edge extending in the plane of a side edge of the 115 first mentioned zone, said zones being defined by contour formations extending substantially transverse to the direction of length of the blank.

20. A spool formed from a single integral 120 sheet of material, including a barrel portion of substantially uniform cross-section formed from a plurality of superposed convolutions, said barrel having concave ends formed from the edges of convolutions successively reduced in width as they approach the center of the spool.

21. A spool formed from a single integral 125 sheet of material, including a barrel portion of substantially uniform cross-section 130

formed from at least one convolution of material, and spaced marginal flanges formed from a plurality of superposed convolutions of material integral with that forming the 5 barrel.

22. A spool formed from a single integral sheet of material, including a barrel portion of substantially uniform cross-section formed from a plurality of superposed 10 convolutions, said barrel having concave ends

formed from the edges of convolutions successively reduced in width as they approach the center of the spool, and spaced marginal flanges formed from a plurality of superposed convolutions of material integral with 15 that forming the barrel.

In testimony whereof I have hereunto set my hand.

ROBERT S. BOLGER.
